DESIGN FOR A MEDICINE CABINET

Anthony J. Danese, Stockton, N. J., assignor of
one-half to James Danese, Stockton, N. J.

Application January 16, 1941, Serial No. 98,131

Term of patent 14 years

To all whom it may concern:

Be it known that I, Anthony J. Danese, a citizen of the United States, residing at Stockton, in the county of Hunterdon and State of New Jersey, have invented a new, original, and ornamental Design for a Medicine Cabinet, of which the following is a specification, reference being had to the accompanying drawing, forming part thereof.

Figure 1 is a perspective view of a medicine

cabinet, the door thereof being closed, showing my new design.

Figure 2 is a view similar to Figure 1 but with the door of the cabinet in open position.

Figure 3 is a side elevational view of the cabinet.

I claim:

The ornamental design for a medicine cabinet, as shown,

ANTHONY J. DANES.
